UNITED STATES PATENT OFFICE.

VINCENT BENDIX, OF CHICAGO, ILLINOIS.

ENGINE-STARTER.

1,288,373.

Specification of Letters Patent. Patented Dec. 17, 1918.

Original application filed December 30, 1912, Serial No. 739,168. Divided and this application filed April 26, 1915. Serial No. 24,028.

To all whom it may concern:

Be it known that I, VINCENT BENDIX, a citizen of the United States, residing at Chicago, in the county of Cook and State of Illinois, have invented certain new and useful Improvements in Engine-Starters, of which the following is a specification, this application being divisional of an application filed by me on December 30, 1912, Serial No. 739,168.

My invention relates to a starter for an engine, more particularly a gas engine and the like, characterized by the employment of a screw-shaft operated by a prime mover such as an electric motor and a pinion screw-threaded upon the shaft and adapted to travel longitudinally in one direction along the shaft into engagement with the rotary member of the engine to be started and to travel longitudinally in the opposite direction after being automatically thrown out of engagement with the engine member when the engine begins to run on its own power.

The object of my invention is to provide an automatic electric switch controlled by the movements of the pinion whereby after a manually operated switch is operated to start the electric motor, the movement of the pinion will cause the automatic switch to be closed and the operator thereby relieved from further operation of his switch so that only a momentary manual operation is required, and whereby also the circuit is automatically broken when the pinion has been retracted a predetermined distance.

In the drawing, Figure 1 is a sectional elevation of my device shown in connection with the wheel driven by the engine such as a fly wheel and showing my invention operating in connection with the starting mechanism, and Fig. 2 a detail plan view of a portion of the starting mechanism including the pinion and screw shaft and illustrating the automatic switch.

Describing the construction shown in the drawing, the engine wheel which is here intended as the fly wheel 1 of a gas engine, is provided on its periphery with teeth 2. The prime mover comprises an electric motor 3 which is here shown as having an extended armature shaft 4 which is in the plane of the engine wheel and in proximity thereto. For a portion of its length this shaft is provided with spiral or screw threads 5 with

which coöperate corresponding threads in the central opening of a pinion 6 adapted to mesh with the teeth 2 of the engine wheel.

The construction and arrangement of the screw shaft and pinion are such that the latter is capable of an advance movement longitudinally of its shaft upon the initial rotation of such shaft by the electric motor and until the consequent advancement of such pinion brings the latter into mesh with the engine wheel, whereupon the continued rotations of the shaft rotate the pinion and thereby rotate and drive the engine wheel. As soon as the engine itself starts on its own power the excess rotation of the wheel as compared with the rotation of the screw shaft will cause the pinion to move laterally back to home position, but that is toward the right in the drawing and to be thereby withdrawn from mesh with the engine wheel.

The motor may be supported in any suitable manner adjacent the engine wheel and in case the device is used in connection with an automobile engine, as herein intended, such support may be a fixed part of the chassis as indicated at 7. The outer or free end of the screw shaft is provided with a suitable bearing 8 in the end of any suitable support such as a bracket 9 which is here shown secured to the body of the motor.

The motor is provided with two supply circuits, one being manually operated and the other automatically. The manually controlled circuit comprises the wires 10 and an interposed manually operated switch shown diagrammatically at 11. In case the device is used in connection with an automobile this switch may be placed upon the dash or elsewhere within easy reach of the driver. The automatic circuit comprises the wires 12 in which is interposed an automatic switch including two stationary contacts 13 and a movable connector blade 14. This blade is mounted upon and carried by a plate 15 which in turn is carried by the pinion 6, with the result that such plate and its blade partake of the movements of such pinion longitudinally of the armature shaft. As shown, this plate is at its lower end formed as a strap 16 adapted to fit within a groove 17 at the inner end of the pinion 6 so that such plate will not rotate but will have only a longitudinal movement. This plate 15 is provided with an opening 18

which is adapted to be engaged by a spring catch 19 whose inner end is slightly in-turned so as to yieldingly engage said arm in order to hold the pinion in its normal position, as shown in full lines in Fig. 1, but to permit said pinion to be released and to be advanced whenever the electric motor is operated. However, this catch device is not necessary but may, if desired, be dispensed with.

Describing the operation of my starter, the first step is the closing of the switch 11 by the driver, with the result that the motor 3 is instantly started and its armature shaft 4, which is also the screw shaft, is rotated. The pinion 6 thereupon moves longitudinally of the shaft into mesh with the engine wheel and when it is fully in mesh, and has reached the end of the threads 5 and abuts against the shoulder 4^a, it will rotate in unison with the armature shaft and consequently drive or rotate the engine wheel. Inertia of the pinion or friction between it and the yoke 16 should prevent rotation of the pinion until it is in mesh, but a slight rotation thereof before it reaches the engine wheel is immaterial.

After the starting of the motor by the push button, the movable connector blade 14 will coöperate with the fixed contacts 13 to close the automatic switch so that the driver or operator may now release the manually operated switch, which will break the circuit which includes the wires 10, the other circuit now supplying the necessary current to the motor. This condition remains until the engine starts under its own power from the explosions, whereupon the pinion 6 will be withdrawn from mesh with the engine wheel in the manner hereinbefore described. At a predetermined point in this longitudinal movement of the pinion the contact between the fixed contacts 13 and movable connector blade 14 is broken and the electric motor will thereupon cease to operate. When the pinion returns to its normal position the spring catch will engage the connector blade 14 and hold the pinion in retracted position.

50 I claim:

1. A starter for gas engines comprising a driving member adapted to coöperate with and drive an engine member, a rotatable member with which said driving member coacts to produce longitudinal travel relative to the rotatable member for automatically moving such driving member into driving engagement with the engine member whenever the rotatable member is rotated, an electric motor for rotating said rotatable member, means for supplying current to said motor, comprising two connections, a manually operated switch in one connection and an automatically operated switch in the 60 other connection whereby current may first

be led to the motor through the manually operated switch and subsequently independently thereof.

2. A starter for gas engines comprising a driving member adapted to coöperate with and drive an engine member, a rotatable member with which said driving member coacts to produce longitudinal travel relative to the rotatable member for automatically moving such driving member into 75 driving engagement with the engine member whenever the rotatable member is rotated, an electric motor whose extended armature shaft constitutes said rotatable member, means for supplying current to said 80 motor, comprising two connections, a manually operated switch in one connection and an automatically operated switch in the other connection whereby current may first be led to the motor through the manually 85 operated switch and subsequently independently thereof, said automatic switch being controlled by said driving member in its movements and adapted to be closed when the driving member is in engagement with 90 the engine member.

3. A starter for engines comprising a screw shaft, a pinion mounted to travel longitudinally thereon and rotarily therewith, an electric motor for rotating the screw shaft, means for supplying current to said 95 motor, comprising two connections, a manually operated switch in one connection and an automatically operated switch in the other connection whereby current may first be led to the motor through the manually 100 operated switch and subsequently independently thereof, said automatic switch being controlled by said pinion in its travel.

4. A starter for engines comprising a 105 screw shaft, a pinion mounted to travel longitudinally thereon and revolve therewith, an electric motor for rotating the screw shaft, means for supplying current to said 110 motor, comprising two connections, a manually operated switch in one connection and an automatically operated switch in the other connection whereby current may first be led to the motor through the manually 115 operated switch and subsequently independently thereof, said automatic switch consisting of a stationary contact and a movable connector blade movable in unison with the connection.

5. A starter for engines comprising a 120 screw shaft, a pinion mounted to travel longitudinally thereon and rotarily therewith, an electric motor for rotating the screw shaft, means for supplying current to said 125 motor, comprising two connections, a manually operated switch in one connection and an automatically operated switch in the other connection whereby current may first be led to the motor through the manually 130 operated switch and subsequently independently

- ently thereof, said automatic switch consisting of a stationary contact and a movable connector blade mounted on and movable with the pinion.
- 5 6. A starter for gas engines and the like, comprising an electric motor having an extended armature shaft, a pinion mounted thereon for longitudinal and rotary movements and adapted to mesh with an engine member, the rotation of the shaft advancing the pinion and an automatic switch and a manually-operated switch for governing the circuit supply to the motor, the automatic switch being controlled by the pinion.
- 10 7. A self starter for gas engines and the like comprising in combination with a toothed wheel operated by the engine, an electric motor, a screw shaft operated thereby, means for supplying current to said motor, comprising two connections, a manually operated switch in one connection and an automatically operated switch in the other connection whereby current may first be led to the motor through the manually operated switch and subsequently independently thereof, a driving pinion actuated by the motor and automatically moved into and out of mesh with said wheel by the operations respectively of the screw shaft and the engine, said automatic switch being controlled by the pinion in its movements and adapted to be closed when such pinion is in mesh with the wheel, a plate carried by the pinion and having contacts forming part of the automatic switch, and a means adapted to yieldingly engage the plate when the pinion is in retracted position.
- 15 8. A self starter for gas engines and the like comprising, in combination with a toothed wheel operated by the engine, an electric motor, a screw shaft operated thereby, means for supplying current to said motor, comprising two connections, a manually operated switch in one connection and an automatically operated switch in the other connection whereby current may first be led to the motor through the manually operated switch and subsequently independently thereof, an automatic switch in the other circuit, a driving pinion actuated by the motor and automatically moved into and out of mesh with said wheel by the operations respectively of the screw shaft and the engine, said automatic switch being controlled by the pinion in its movements and adapted to be closed when such pinion is in mesh with the wheel, a plate carried by the pinion and having contacts forming part of the automatic switch, and a spring hook adapted to engage the plate when the pinion is in retracted position.
- 20 9. A self-starter for gas engines and the like comprising an electric motor, means driven by the motor for driving the engine comprising a member having rotary move-
- 25 ment and a movement of translation to connect and disconnect the motor and engine, said member being so connected to the motor as to receive rotation and translation therefrom, connections from a source of current to the motor comprising a manually operated switch and electrical connections with said motor comprising an automatic switch controlled by the movement of translation of said member.
- 30 10. A self-starter for gas engines comprising a rotary electric motor, an element rotated by said motor and having a motion of translation into and out of contact with a rotary member of the engine, connections whereby the rotation of the motor drives said element into operative engagement with said member of the engine and the operation of the engine drives said element out of operative connection therewith, a manually controlled connection from a source of current to the motor and a connection from the source of current to the motor comprising an automatic switch which is closed by the movement of said element toward said member of the engine and opened by the reverse movement thereof.
- 35 11. A starter for gas engines comprising a driving member adapted to be moved into engagement with and to drive an engine member, an electric motor having an extended armature shaft on which said driving member is mounted, and means for supplying current to said motor comprising two connections, a manually operated switch in one connection and an automatically operated switch in the other connection whereby current may first be led to the motor through the manually operated switch and subsequently independently thereof.
- 40 12. A starter for gas engines comprising in combination with a toothed engine wheel, a pinion adapted to be moved into engagement with and to drive such engine wheel, an electric motor having an extended armature shaft on which said pinion is mounted, and means for supplying current to said motor comprising two connections, a manually operated switch in one connection and an automatically operated switch in the other connection whereby current may first be led to the motor through the manually operated switch and subsequently independently thereof.
- 45 13. A starter for gas engines comprising an electric motor, a pinion rotated by said motor and having a motion of translation whereby when current is supplied to the motor such pinion is moved into engagement with a rotary member of the engine to be started, and means for supplying current to said motor comprising two connections, a manually operated switch in one connection and an automatically operated switch in the other connection whereby current may first be supplied to the motor through the manually operated switch and subsequently independently thereof.
- 50 14. A self-starter for gas engines comprising an electric motor, a pinion rotated by said motor and having a motion of translation whereby when current is supplied to the motor such pinion is moved into engagement with a rotary member of the engine to be started, and means for supplying current to said motor comprising two connections, a manually operated switch in one connection and an automatically operated switch in the other connection whereby current may first be supplied to the motor through the manually operated switch and subsequently independently thereof.
- 55 15. A self-starter for gas engines comprising an electric motor, a pinion rotated by said motor and having a motion of translation whereby when current is supplied to the motor such pinion is moved into engagement with a rotary member of the engine to be started, and means for supplying current to said motor comprising two connections, a manually operated switch in one connection and an automatically operated switch in the other connection whereby current may first be supplied to the motor through the manually operated switch and subsequently independently thereof.
- 60 16. A self-starter for gas engines comprising an electric motor, a pinion rotated by said motor and having a motion of translation whereby when current is supplied to the motor such pinion is moved into engagement with a rotary member of the engine to be started, and means for supplying current to said motor comprising two connections, a manually operated switch in one connection and an automatically operated switch in the other connection whereby current may first be supplied to the motor through the manually operated switch and subsequently independently thereof.
- 65 17. A self-starter for gas engines comprising an electric motor, a pinion rotated by said motor and having a motion of translation whereby when current is supplied to the motor such pinion is moved into engagement with a rotary member of the engine to be started, and means for supplying current to said motor comprising two connections, a manually operated switch in one connection and an automatically operated switch in the other connection whereby current may first be supplied to the motor through the manually operated switch and subsequently independently thereof.

- be led to the motor through the manually operated switch and subsequently independently thereof.
14. A starter for engines comprising a screw shaft, a pinion mounted to travel longitudinally thereon and revolve therewith, an electric motor for rotating the screw shaft, means for supplying current to said motor, comprising two connections, a manually operated switch in one connection and an automatically operated switch in the other connection whereby current may first be led to the motor through the manually operated switch and subsequently independently thereof, said automatic switch consisting of a stationary contact and a movable connector having frictional contact with the pinion and movable therewith.
15. A starter for engines comprising a screw shaft, a pinion mounted to travel longitudinally thereon and revolve therewith, an electric motor for rotating the screw shaft, means for supplying current to said motor, comprising two connections, a manually operated switch in one connection and an automatically operated switch in the other connection whereby current may first be led to the motor through the manually operated switch and subsequently independently thereof, said automatic switch consisting of a stationary contact and a movable connector provided with a strap having frictional contact with the pinion and movable therewith.
16. A starter for engines comprising a screw shaft, a pinion mounted to travel longitudinally thereon and revolve therewith, an electric motor for rotating the screw shaft, means for supplying current to said motor, comprising two connections, a manually operated switch in one connection and an automatically operated switch in the other connection whereby current may first be led to the motor through the manually operated switch and subsequently independently thereof, said automatic switch consisting of a stationary contact and a movable connector provided with a strap having frictional contact with the pinion and movable therewith, said pinion having a circumferential groove with which said strap co-operates.
17. A starter for engines comprising a rotatable screw shaft, a pinion screw-threaded thereon for longitudinal movement thereon and rotary movement therewith, and means mounted on and movable with the pinion for retarding the rotary movement thereof.
18. A starter for engines comprising a rotatable screw shaft, a pinion screw-threaded thereon for longitudinal movement thereon and rotary movement therewith, and means mounted on the pinion and having frictional engagement therewith for retarding the rotary movement thereof.
19. A starter for engines comprising a rotatable screw shaft, a pinion screw-threaded thereon for longitudinal movement thereon and rotary movement therewith, and means for exerting a constant friction upon the pinion for retarding the rotary movement thereof.
20. A starter for engines comprising a rotatable screw shaft, a pinion screw-threaded thereon for longitudinal movement thereon and rotary movement therewith, and a non-rotary member in constant frictional contact with the pinion for retarding the rotary movement thereof.
21. A starter for engines comprising a rotatable screw shaft, a pinion screw-threaded thereon for longitudinal movement thereon and rotary movement therewith, a member in constant frictional contact with the pinion for retarding the rotary movement thereof, and means for preventing rotary movement of said member.
22. A starter for engines comprising a rotatable screw shaft, a pinion screw-threaded thereon for longitudinal movement thereon and rotary movement therewith, and having a circumferential groove, and a non-rotary member received by said groove and imparting frictional resistance to the pinion for retarding the rotary movement thereof.
23. A starter for engines comprising a rotatable screw shaft, a pinion screw-threaded thereon for longitudinal movement thereon and rotary movement therewith, and having a circumferential groove, and a non-rotary strap capable of longitudinal movement and engaging said groove to impart frictional resistance to the rotary movement of the pinion.
24. A starter for engines comprising a rotatable screw shaft, a pinion screw-threaded thereon for longitudinal movement thereon and rotary movement therewith, and having at one end an extension provided with a circumferential groove, and a non-rotary strap capable of longitudinal movement and engaging said groove to impart frictional resistance to the rotary movement of the pinion.
25. A starter for engines comprising a rotatable screw shaft, a pinion screw-threaded thereon for longitudinal movement thereon and rotary movement therewith, and means movable longitudinally with the pinion for retarding the rotary movement thereof.
26. A starter for engines comprising a rotatable screw shaft, a pinion screw-threaded thereon for longitudinal movement thereon and rotary movement therewith, and means frictionally engaging the pinion and movable longitudinally therewith for retarding its rotary movement.
27. An engine starter comprising a rotatable member, an actuating member mounted thereon for rotary movement there-

with and longitudinal movement thereof, and means movable in unison with said actuating member and engaging a portion thereof for retarding its rotary movement.

5 28. In an engine starter, the combination, with an electric motor and an electrical circuit therefor including a switch, of a transmission mechanism driven by the motor and arranged between such motor and a part of

10 the engine to be started, said mechanism including a device adapted to move longitudinally to operatively engage such engine part and to be rotated by the motor to drive such engine part and to be automatically disengaged therefrom when the engine starts on its own power, and said switch including means actuated after the starting of the motor for closing the switch when said device and engine part are in driving engagement.

20 29. In an engine starter, the combination, with an electric motor and an electrical circuit therefor including a switch, of a transmission mechanism driven by the motor and arranged between such motor and a part of the engine to be started, said mechanism including a device mounted to operatively engage such engine part to drive the same and to be automatically disengaged therefrom when the engine starts on its own power, and means controlled by said mechanism for closing said switch when said device and engine part are in driving engagement.

30 30. In an engine starter, the combination, with an electric motor and an electrical circuit therefor including a switch, of a transmission mechanism driven by the motor and arranged between such motor and a part of the engine to be started, said mechanism including a device adapted to move longitudinally to operatively engage such engine part and to be rotated by the motor to drive such engine part and to be automatically disengaged therefrom when the engine starts on its own power, and means controlled by said mechanism for automatically opening the switch and thereby breaking the circuit when said device is so disengaged from the engine part.

50 31. In an engine starter, the combination, with an electric motor, and an electrical circuit therefor including a switch, of a transmission mechanism driven by the motor and arranged between such motor and a gear on the machine to be started, said mechanism including a pinion mounted for longitudinal movement to mesh with said gear and for rotary movement to drive such gear to start the engine, said pinion being adapted to be automatically demeshed from the gear when the engine starts on its own power, and means actuated by said mechanism for controlling said switch.

55 32. In an engine starter, the combination, with an electric motor, and an electrical cir-

cuit therefor including a switch, of a transmission mechanism driven by the motor and arranged between such motor and a gear on the engine to be started, said mechanism including a pinion mounted for longitudinal movement to mesh with said gear and for rotary movement to drive such gear to start the engine, and a screw member on which the pinion is screw-threaded, said pinion being adapted to be automatically demeshed by screw action on said screw member when the engine starts on its own power, and means actuated by said mechanism for controlling said switch.

33. In an engine starter, the combination, with an electric motor and an electrical circuit therefor including a switch, of a transmission mechanism driven by the motor and arranged between such motor and a part of the engine to be started, said mechanism including a device adapted as a result of the operation of the motor to move longitudinally to operatively engage such engine part and to be rotated by the motor to drive such engine part and to be automatically disengaged therefrom when the engine starts on its own power, and said switch including an electrical connector adapted to control the same switch and having a yoke connection with said mechanism.

34. In an engine starter, the combination, with an electric motor and an electrical circuit therefor including a switch, of a transmission mechanism driven by the motor and arranged between such motor and a part of the engine to be started, said mechanism including a device adapted as a result of the operation of the motor to move longitudinally to operatively engage such engine part and to be rotated by the motor to drive such engine part and to be automatically disengaged therefrom when the engine starts on its own power, and said switch having means, including a member having frictional contact with a part of said mechanism, for controlling said switch.

35. In an engine starter, the combination, with an electric motor and an electrical circuit including a switch therefor, of a transmission mechanism driven by the motor and arranged between such motor and a part of the engine to be started and adapted, as a result of the operation of the motor, to be operatively engaged with a part of the engine to be started, said mechanism including a driving shaft driven by the motor and a member mounted on the shaft for longitudinal movement thereof and rotary movement therewith, and said switch including means connected with said member for controlling the switch to open and close the circuit.

36. In an engine starter, the combination, with an electric motor and an electrical circuit including a switch therefor, of a transmission mechanism driven by the motor and

5 arranged between such motor and a part of the engine to be started and adapted, as a result of the operation of the motor, to be operatively engaged with a part of the engine to be started, said mechanism including a rotatable screw shaft, a pinion screw-threaded thereon and adapted to mesh with said engine part and to be automatically demeshed therefrom by screw action on said 10 shaft, and said switch including means actuated by said mechanism for controlling the switch.

37. In an engine starter, the combination, with an electric motor and an electrical circuit including a switch therefor, of a transmission mechanism driven by the motor and arranged between such motor and a part of the engine to be started and adapted, as a result of the operation of the motor, to be 20 operatively engaged with a part of the engine to be started, said mechanism including a driving shaft driven by the motor and a member mounted on the shaft for longitudinal movement thereof and rotary movement therewith, and means connected with said 25 member for controlling said switch to open and close the circuit, said switch comprising a connector having a yoke connection with said device and movable therewith in its 30 said longitudinal movement.

38. In an engine starter, the combination, with an electric motor and an electrical circuit including a switch therefor, of a transmission mechanism driven by the motor and arranged between such motor and a part of the engine to be started and adapted, as a result of the operation of the motor, to be 35 operatively engaged with a part of the engine to be started, said mechanism including a driving shaft driven by the motor and a 40

member mounted on the shaft for longitudinal movement thereof and rotary movement therewith, and means connected with said member for controlling said switch to open and close the circuit, said switch comprising a connector bodily movable with said device in the longitudinal movement of the latter. 45

39. In an engine starter, the combination, with an electric motor and an electrical circuit therefor including a switch, of a transmission mechanism driven by the motor and arranged between such motor and a part of the engine to be started, said mechanism including a device adapted to move longitudinally to operatively engage such engine part 50 and to be rotated by the motor to drive such engine part and to be automatically disengaged therefrom when the engine starts on its own power, and combined means for controlling said switch and for holding said 55 device in retracted position.

40. In an engine starter, the combination, with an electric motor and an electrical circuit therefor including a switch, of a transmission mechanism driven by the motor and arranged between such motor and a part of the engine to be started, said mechanism including a device adapted to move longitudinally to operatively engage such engine part 60 and to be rotated by the motor to drive such 70 engine part and to be automatically disengaged therefrom when the engine starts on its own power, and combined means for holding said device in retracted position and the switch in open position.
